Louis E. Amborn, Willows, Calif.

Application February 7, 1958, Serial No. 49,534

Term of patent 14 years

(Cl. D14—3)

FIG. 1

FIG. 2

FIG. 3

FIG. 4

FIG. 5

Figure 1 is a perspective view of a removable semi-body adaptor unit for pick-up trucks, embodying my new design, the broken line showing of a pick-up truck being for purposes of illustration only;

Figure 2 is a rear elevational view;

Figure 3 is a front elevational view;

Figure 4 is a right side elevation view, the opposite being substantially the same; and

Figure 5 is a top plan view.

I claim:

The ornamental design for a removable semi-body adaptor unit for pick-up trucks, as shown, and described.
